BRASSIERE

Raymond Pioli, Floral Park, N.Y., assignor to Maiden Form Brassiere Co., Inc.

Filed Mar. 3, 1960, Ser. No. 59,604

Term of patent 14 years

(Cl. D20—4)

FIG. 1

FIG. 2

Fig. 1 is a front perspective view of a brassiere showing my new design; and

Fig. 2 is a rear perspective view thereof.

The conventional shoulder straps are shown broken away for convenience of illustration and the dotted lines seen through the transparent lace areas indicate seam stitching.

I claim:

The ornamental design for a brassiere, as shown and described.
